Inventor:

William W. Galbreath,
By Dunnington Lee, Clifton & Hales,
Atty's.

UNITED STATES PATENT OFFICE.

WILLIAM W. GALBREATH, OF WARREN, OHIO, ASSIGNOR TO THE YOUNGSTOWN
PRESSED STEEL COMPANY, OF WARREN, OHIO, A CORPORATION OF OHIO.

LATH-SPACING NAIL.

Application filed April 28, 1927. Serial No. 187,288.

This invention relates to improvements in lath spacing nails, or the like, and more especially to such nails adapted for attaching expanded metal lath to a wall and spacing the same therefrom.

For example, the improved nails are very well adapted for fastening lath to the outer wall or sheathing of a building and spacing the same therefrom, such lath being used for supporting a stucco finish.

By the use of my improved nails, the putting in place of expanded metal lath is greatly facilitated. The nails with the spacing means may be easily and cheaply made and are simple in construction so that any mechanic can easily understand the use of the same.

Other features and advantages of my invention will appear more fully as I proceed with my specification.

In that form of device embodying the features of my invention shown in the accompanying drawing,

Fig. 1 is a plan view of a sheet-metal blank from which the spacer of my nail is formed, Fig. 2 shows in perspective the nail complete with the spacer in place, Fig. 3 is a similar view showing a strand of the lath clamped by the nail, and Fig. 4 is a view in elevation of a nail in place supporting the lath.

As shown in the drawings, 10 indicates a substantially rectangular blank of sheet-metal from which the spacer is formed. This blank is provided with the two ears 10^a, 10^b and a central aperture 10^b. The two ends 10^c of the blank 10 are bent upwardly at right angles on the lines indicated by 10^a, 10^b to form a spacer as shown in Figs. 2, 3 and 4. In the completed spacer therefore the two portions 10^a, 10^b lie parallel with each other and at right angles to the central bottom, or base, portion 10^c.

11 indicates a nail with a relatively fine sharp point 11^a and a flat head 11^b. The nail is inserted through the hole 10^b as shown in Fig. 2, and the head 11^b is large enough so that as the nail is forced through the hole, such head will clamp a strand 12 of the lath between its edge and the upwardly projecting ears 10^a of the spacer, as shown in Fig. 3.

In operation, the nail may be partially inserted in the hole 10^b, as shown in Fig. 2.

A strand 12 of the lath may then be hooked over the nail and the point of the nail inserted in the sheathing, or wall, of a building by hand pressure sufficiently to hold the same temporarily in place. It will be seen that this operation may be performed by one hand while the other holds the lath in position. When thus inserted, the parts will be held in correct position to permit easy nailing. When the nail is hammered in, the strand 12 hooked over the nail becomes clamped between the head 11^b and the ears 10^a, as shown in Fig. 3, and at the same time the nail is driven into the wall, or sheathing, of the building to hold the lath firmly in place, the portions 10^c of the spacer spacing the same from the wall.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. A device of the character described comprising, a spacer having a base portion provided with an aperture and two outwardly projecting spacing walls joined to the edges of said base portion, said walls having ears on their outer edges, and a nail with a head adapted to be inserted through the aperture in the base portion, the head of said nail adapted to clamp a strand of metal lath against the outer edges of the spacing walls between the nail and the ears when the same is driven home.

2. A device of the character described comprising, a spacer formed from a substantially rectangular blank of sheet-metal, said spacer consisting of a central perforated base portion and two spacing walls bent outwardly at the edges of said base portion, said walls being provided with ears on their outer edges, and a nail with a head adapted to be inserted through the aperture in said base portion, the head of said nail adapted to clamp a strand of metal lath against the outer edges of the spacing walls and between the ears and the nail when the same is driven home.

3. A device of the character described comprising, a spacer consisting of a perforated base portion and a spacing member

projecting outwardly therefrom, an ear on the outer edge of said spacing member, and a nail with a head adapted to be inserted through the aperture in the base portion, the head of said nail adapted to clamp a strand of metal lath against the outer edge of the spacing member and between the ear and the nail when the same is driven home.

4. A device of the character described comprising, a spacer consisting of a substantially rectangular flat perforated base portion, two substantially parallel outwardly projecting spacing walls joined to the edges of said base portion and lying at substantially right angles thereto, ears on the outer edges of said spacing walls, and a nail with a head adapted to be inserted through the aperture in the base portion, the head of said nail adapted to clamp a strand of metal lath against the outer edges of the spacing walls and between the nail and the ears when the same is driven home.

5. A device of the character described comprising, a spacer consisting of a sub-

stantially rectangular flat perforated base portion, an outwardly projecting spacing wall joined to the edge of said base portion and lying substantially at right angles thereto, an ear on the outer edge of said spacing wall, and a nail with a head adapted to be inserted through the aperture in said base portion, the head of said nail adapted to clamp a strand of metal lath against the outer edge of the spacing wall and between the ear and the nail when the same is driven home.

6. A spacer and support adapted for applying expanded metal lath, comprising a base web and spaced flanges projecting therefrom and equipped with ears, said web having a perforation therethrough adapted to receive a nail with space between the nail and ears for an intervening member of the metal lath.

In witness whereof, I have hereunto set my hand this 18th day of April, 1927.

WILLIAM W. GALBREATH.
